UNITED STATES PATENT OFFICE.

EDWARD H. OVERHOLT, OF GALESBURG, ILLINOIS.

ENGINE-STARTER.

1,168,221.

Specification of Letters Patent. Patented Jan. 11, 1916.

Application filed October 2, 1914. Serial No. 864,625.

To all whom it may concern:

Be it known that I, EDWARD H. OVERHOLT, a citizen of the United States, and a resident of Galesburg, in the county of Knox and State of Illinois, have invented a new and useful Engine-Start, of which the following is a specification.

My improvements relate to starters for internal combustion engines, and particularly to that type thereof which are adapted to rotate the engine-shaft to insure the firing of the initial charge, and to be rewound by the resultant starting of the engine.

One of the objects of the invention is to provide a starter having but very few parts and each thereof of such nature that it will be durable and not liable to become broken or out of order.

Another object—and a special one—is to provide a novel motor spring and co-acting mechanism, each of which acts upon the other during the different phases of the operation.

More specifically stated, I have departed from the usual flat helical spring generally utilized as the motor-spring, and instead thereof employ a spiral spring or spring having compression and expansion in the line of its axis, as the power-storing spring for imparting the initial impulses to the crank-shaft of the engine, the compression and expansion not being due, however, to pressure, but to the fact that one end of the spring rotated about its axis while the other is held from rotation.

It is a further object to utilize said spring to disengage clutch-mechanism, this being due to the lengthening of the spring by turning one of its ends as above described, while the other is held from rotation whereby the number of coils is increased, but their diameters diminished.

It is an object to provide a novel motor-shaft arrangement, on which shaft the motor-spring is spirally coiled.

It is an object to provide a spring-shaft parallel to the engine-shaft and to provide a simple gear by which either shaft is adapted to actuate the other.

It is a further object to utilize the axial contractile force of the motor-spring to throw one clutch member into engagement with another, to place said members in position for rotating the engine-shaft to start the engine.

It is an object to provide means for hold-

ing one of the rewinding clutches from engaging the other until the engine is running under its own power.

It is another object to provide a novel friction clutch for imparting the initial impulse to the engine-shaft, said clutch to be driven by the motor-spring.

A still further object is to provide a spring of the character described, both ends of which are secured to some rotating or revoluble element, one of said elements being adapted to rewind the spring and the other to receive movement from said spring.

Another object is to provide means whereby the tension of the spring may be regulated.

Another object is to provide a novel trigger for releasing the motor-spring to impart motion to interposed means which will impart the initial impulse to the engine-shaft, the trigger being further employed to prevent engagement of the rewind clutches, as earlier herein referred to.

A further object is to provide means for preventing the motor-spring from unwinding when one of the rewind clutch-members disengages from the other.

It is an object to provide novel means for manually cranking the engine, which means is preferably to be left permanently mounted on the starter.

It is an object to provide novel means for connecting the starter-shaft with the engine-shaft.

It is an object to provide a starter in which the motor-spring is not contained within the casing.

To provide a compact casing which may be readily and easily attached to or removed from the car, and which presents no unsightly or unattractive features, constitutes still another object.

To so construct, arrange and organize the parts of the starter that it may readily be taken apart or the parts readily assembled by mechanics unfamiliar with its construction, constitutes still another object.

It is a further object to so construct and arrange the starter elements that no brake is necessary.

It is a still further object to increase or diminish the tension and thereby regulate the power of the motor-spring.

Minor objects will be in part obvious and in part specifically pointed out.

Concise stated, the general object of the

invention is to simplify and improve the construction and increase the efficiency and utility of devices of this character.

By way of example an engine-starter constructed in accordance with the principles of my invention is hereinafter described, with reference to the accompanying drawings illustrating it in the best form now known to me, in which:

10. Figure 1 is a side elevation of my improved engine-starter as it appears on a fragment of an automobile; Fig. 2, a vertical central section, partly in elevation, of a preferred embodiment of my improvements, showing also a fragment of an engine-crank-shaft, (hereinafter termed the "engine-shaft") and the means of connecting the motor-shaft or cranking-shaft thereto; Fig. 3, a fragmental detail of the 15 motor-spring, spring-shaft, and cranking sleeve; Fig. 4, a front end view, the front casing member and cap removed; Fig. 5, a vertical sectional view, taken in the plane of the line 5-5 in Fig. 3; Fig. 6, a vertical sectional view, taken in the plane of the line 20 6-6 in Fig. 3; Fig. 7, a perspective detail of one of the halves of a split assembling ring hereinafter referred to; Fig. 8, a perspective detail of the cap which performs 25 the function of a front bearing for the spring-shaft; Fig. 9, a perspective detail of the cranking sleeve and starting-pinion; Fig. 10, an enlarged detail of the trigger 30 lever and the tripping block actuated thereby; Fig. 11, a transverse sectional view, taken in the line 11-11 in Fig. 3; Fig. 12, an enlarged perspective detail of the trigger; and Fig. 13, an enlarged perspective detail of the clutch-hold-out.
35. Coming now to a detailed description of the drawings above briefly referred to, and indicating by a distinguishing reference numeral each part therein shown, 2 indicates a casing comprising a front 3 and back 4, secured together by screws 5.
40. 6 designates an end bearing for the motor-shaft.
45. 7 designates an end bearing for the cranking sleeve.
50. 8 represents a bearing for the clutch-hold-out.
55. 9 indicates a bearing for the pawl.
60. 10 indicates the spring-shaft, preferably having at its rear or inner end a plurality of transverse openings 11. It is supported near its outer end in a cranking sleeve 12 and at its outer end in a cap 13 secured by bolts 14 to the front casing-member 3. The sleeve 12 is supported in the bearing 7.
65. 15 designates the motor-spring, consisting of a torsional coil-spring the turns of which are substantially equal in diameter throughout its length and the compression and expansion of which is in the line of its axis. Its inner end is formed with an

eye or loop which engages the shank of a bolt 16 which passes through a selective one of the holes 11 in the shaft 10, whereby it is held to rotate with said shaft.

17 is a nut on the bolt 16.

70. The front end of the spring is formed with an eye, which engages a bolt 18 which is threaded into the arm of the cranking-sleeve 12. The direction of rotation of the shaft 10 is always the same; to-wit, seen 75 from the front of the machine, counter-clockwise.

19 designates the starting-pinion suitably fixed on the cranking-sleeve 12 and provided on its inner face with one or more pins 20.

80. 21 indicates a spring-locking ratchet-wheel fixed on the shaft 10. On its outer face this wheel is provided with clutch-teeth 22.

85. 23 indicates a rewinding gear-wheel provided on its inner face with clutch-teeth 24 adapted for engagement with the teeth 22. The outer face of the wheel 23 is provided with a hub 25 having a peripheral groove 26 which receives the halves of a split ring 27 which holds said gear-wheel 23 in place. 90 The ring 27 is held in place by the cap 13.

28 designates the motor-shaft, the forward end of which is mounted in a bushing 29 in the bearing 6 in the casing.

95. 30 designates the usual crank-handle clutch pin.

31 designates one member of a universal joint, keyed on the shaft 28.

100. 32 indicates a hub loosely mounted on the shaft 28. 33, 33 indicate bolts threaded therethrough and into the face of the starting spur-wheel 34 which is loosely mounted on the shaft 28. The heads of the bolts 33 act as stop pins for limiting the movement of friction cranking dogs 35 fulcrumed each 105 on the stem of a bolt 36.

110. 37 indicates the cranking drum, keyed on the motor-shaft 28 and the internal surface of the annular flange of which is adapted to be frictionally engaged by the dogs 35.

115. 38 designates the rewind pinion, also keyed on the shaft 28.

39 indicates a trigger, pivoted at 40 to the casing member 4.

41 indicates a tripping-lever to which is 115 fixed a tripping-block 42.

43 indicates a trigger-return spring.

120. 44 represents a clutch-hold-out, preferably in the form of a bell-crank and fulcrumed at 44' (Fig. 11) on the boss 8.

45 is a locking pawl, pivoted at 46 to the boss 9, and 47 represents a spring for holding said pawl in engagement with the ratchet-wheel 21.

125. 48 designates a universal drive-shaft on the forward end of which is keyed the second member 49, of the universal joint the other member of which has been designated by 31.

130. 50, 50 indicate coupling pins, their shanks

fixed in the member 49 and their heads loosely mounted in sockets in the member 31.

51 designates a knuckle secured by a pin 52 on the motor-shaft, and 53 is a knuckle on the end of the engine-shaft 54.

55 is the knuckle-joint pin.

The operation is as follows: Assume the 10 starter elements to be in the relative positions shown in Fig. 2, wherein the motor-spring is in position to be wound. The engine-shaft 54 will impart clockwise movement to the universal shaft 48, then to the motor-shaft 28 and thereby to the rewind 15 pinion 38 which meshing with the spur-wheel 23 will through the clutch 24—22 rotate the shaft 10 counter clockwise and wind the spring 15 through the bolt 16 the other 20 end of the spring being held stationary, by the cranking-sleeve 12, which itself is held 25 stationary by the pins 20 being locked by the trigger. This operation will continue until the number of coils in the spring have been increased and the latter correspondingly lengthened until it draws the clutch-member 22 away from the clutch-member 24, when the pawl 45 engages the ratchet-wheel 21, holding the spring in wound and energized position. The engine-shaft continues 30 to rotate, with all other parts running idle, and the operator may permit it to so run as long as he desires. Now assume the engine 35 to have been stopped, and the spring to be in the last described position. The operator in starting will move the tripping-lever 41 upward to the position shown by Fig. 5, to move the tripping-block 42 to trip the trigger 39, releasing the pin 20 and thereby the starting-pinion 19. This pinion being keyed 40 to the sleeve 12, and said sleeve connected by the bolt 18 to the motor-spring, will simultaneously release the latter and it in turn will simultaneously impart rotary movement to the cranking-sleeve and thereby to 45 the cranking or starting pinion 19, which, meshing with the starting-spur 34, will impart rotary movement to the hub 32, and through the bolts 36 and centrifugally actuated friction dogs 35 will impart like 50 movement to the friction-drum 37, and this being fixed on the starter-shaft 28 will impart like movement to the shaft 48 and thus crank the engine. It is desirable that the clutch-member 22 be temporarily held out 55 of engagement with the clutch-member 24, and this will be accomplished by reason of the operator continuing to hold the tripping lever 41, during which time the trigger 39 will act on the hold-out-dog or clutch-hold-out 60 44 to cause it to hold out the clutch-member 22 from the clutch-member 24 until the spring has exerted all its stored energy and the engine is running under its own power, whereupon it may be released and 65 the clutch-members 22—24 allowed to en-

gage, thus rewinding the spring by the method previously explained.

Should it become necessary to manually crank the engine, a crank 55 may be applied to the cranking pins on the shaft 28 and the motion will be transmitted directly through to the engine-shaft. As soon as the engine begins running under its own power it will operate the universal-shaft and motor-shaft and thereby rewind the motor-spring in the manner hereinbefore described.

It has been thought neither necessary nor best to enlarge this specification and the accompanying drawings with descriptions and illustrations of modifications which are neither essential to nor form any part of the invention, the object hereof being to instruct others skilled in the art to understand the nature of and to carry out the invention in the form at present preferred by me, in which form it has given satisfactory results. Moreover, many of the details and combinations illustrated are not essential to the invention, broadly considered. All this will be indicated in the claims hereof, wherein the omission of an element or the non-inclusion of reference to the detail features of the elements mentioned is intended to be a formal declaration of the fact that the omitted features or elements are not essential to the invention covered by that claim.

What I do claim is:

1. In combination in an engine-starter, an engine-shaft, a motor-shaft, a spring-shaft parallel with the motor-shaft, a spring 100 coiled on the spring-shaft, a cranking-sleeve rotatable on the spring-shaft and operable by said spring, a pinion fixed on said sleeve, and starter elements interposed between said motor-shaft and spring-shaft, said motor-shaft adapted to be actuated by said engine-shaft, said starter elements adapted to be actuated by said cranking-pinion, said spring-shaft adapted to be actuated by said 105 starter elements, and said spring adapted to be wound by said spring-shaft.

2. In combination in an engine-starter, an engine-shaft, a motor-shaft connected therewith, a spring-shaft parallel with the motor-shaft, a spring coiled on the spring-shaft, a 115 cranking-sleeve on said spring-shaft and connected with one end of said spring, the other end of the spring fixed to said spring-shaft, a pinion fixed on said sleeve, and starter elements interposed between said 120 pinion and motor-shaft and actuatable by said spring to ultimately actuate the engine-shaft.

3. In combination in an engine-starter, an engine-shaft, a motor-shaft connected therewith, a spring-shaft, a torsion spring coiled longitudinally thereof and thereon, a cranking-sleeve on said spring-shaft and operable by said spring, a pinion fixed on said sleeve, and starter elements interposed between said 125 130

- spring-shaft and motor-shaft, said engine-shaft adapted to actuate the motor-shaft, said motor-shaft adapted to actuate said starter-elements, and said starter-elements adapted to store energy in said spring.
4. Combined in an engine-starter, a spring-shaft, a torsion-spring coiled longitudinally thereof and thereon, a motor-shaft, and means interposed between said shafts whereby either may impart rotary motion to the other, said means including a friction-drum and a friction-dog normally in contact with said drum and operable by said spring.
5. In an engine-starter, a spring-shaft, a spring coiled thereon, a clutch-member fixed on said shaft, a clutch-member adapted for engagement with the one recited, a motor-shaft, and starter elements interposed between said spring and motor-shaft, said spring adapted to elongate and thereby draw one of said clutch-members out of engagement with the other.
6. In an engine-starter, co-acting clutch-members, a spring-shaft engaged with one of them, a spring adapted to move said shaft longitudinally and thereby disengage said clutch-members, a motor-shaft, and engine spring-rewinding elements intermediate said clutches and motor-shaft, adapted to operate said clutch-members when they are engaged.
7. In an engine-starter, in combination, a spring-shaft, a spring coiled longitudinally on said shaft and adapted to decrease in length as it is unwound, one of its ends secured to said shaft, a cranking-sleeve fixed to said spring and operable thereby, a motor-shaft, and starter elements interposed between said sleeve and motor-shaft and actuatable by said sleeve.
8. In an engine-starter, in combination, a cranking-sleeve, a spring-shaft, a spring coiled longitudinally of and on said shaft and adapted to increase in length as it is wound, one of its ends secured to said sleeve and the other to said shaft, a motor-shaft, and starter mechanism interposed between said sleeve and motor-shaft and actuatable by said sleeve.
- 50 9. In an engine-starter, in combination, a cranking-sleeve, a spring-shaft, a spring coiled spirally thereon, one of its ends secured to said sleeve and the other to said shaft, a motor-shaft, and starter mechanism interposed between said sleeve and motor-shaft and actuatable by said sleeve, said spring adapted to increase in length as it is wound and to thereby move the spring-shaft longitudinally.
- 60 10. In an engine-starter, a motor-spring, capable of being elongated axially, co-acting clutch-members, means actuated by said spring as it elongates for drawing one of them out of engagement with the other,

means for holding the drawn member in said position, and rewinding elements adapted for actuation by said clutch-members when they are engaged.

11. In an engine-starter, a motor-spring, capable of being elongated axially, co-acting clutch-members, means actuated by said spring as it elongates for drawing one of them out of engagement with the other, a hold-out adapted to retain the drawn member in said position, and rewinding elements adapted for actuation by said clutch-members when they are engaged.

12. In an engine-starter, a motor-spring, capable of axial elongation, co-acting clutch members, motor-spring actuated means for drawing one of them out of engagement with the other, due to the elongation of the spring, manually actuatable means adapted to retain the drawn member in said position while the spring is unwinding, engine-starter elements actuated by said spring, and spring-winding elements operatively engaged with said clutch-members.

13. In combination in an engine-starter, an elongated spring-shaft, a starter-spring coiled longitudinally thereof and thereon and one of its ends secured thereto, a cranking-sleeve to which the other end of said spring is secured rotatably mounted on said spring shaft, a cranking-pinion driven by said sleeve, a cranking-spur driven by said pinion, and a motor-shaft driven by said spur.

14. In combination in an engine-starter, an elongated spring-shaft, a starter-spring coiled longitudinally thereof and thereon, a cranking-sleeve to which one end of said spring is secured, a cranking-pinion driven by said sleeve, a cranking-spur driven by said pinion, centrifugally actuated means driven from said spur, and a motor-shaft driven by said centrifugally actuated means.

15. In combination with an engine-shaft, a motor-shaft connected thereto, a rewind-pinion driven thereby, a spur-wheel in mesh therewith, clutch mechanism driven by said spur, a spring-shaft driven by said clutch mechanism, and a spiral-spring coiled on said spring-shaft and adapted to be coiled thereby.

16. In combination with an engine-shaft, a motor-shaft connected therewith, a rewind-pinion driven thereby, a spur-wheel in mesh therewith, a clutch-member driven by said spur, a motor-spring, a sleeve to which one of its ends is secured, a spring-shaft to which its other end is secured, a clutch-member connected with said spring-shaft and adapted for actuation by the clutch-member recited, a cranking-pinion and means carried by said pinion for locking said sleeve from rotation.

17. In combination with an engine-shaft,

- a motor-shaft connected thereto, a rewind pinion driven thereby, a spur-wheel in mesh therewith, a clutch-member driven by said spur, a torsion motor-spring, a sleeve to 65
 5 which one of its ends is secured, an elongated shaft on which said spring is coiled and to which its other end is secured, a clutch-member connected with said spring-shaft and adapted for actuation by the 70
 10 clutch-member recited, and means for locking said sleeve from rotation.
18. In an engine-starter, a spring-shaft, a spring coiled thereon and adapted for elongation in the direction of its axis, co- 75
 15 acting clutch-members one of which is drawn from the other by the elongation of said spring, a motor-shaft, and starter elements interposed between said spring and motor-shaft.
19. In an engine-starter, a tripping lever, a trigger actuated thereby, a starting and locking-pinion adapted to be released by the trigger, a spur in mesh with said pinion, friction-dogs, a friction-drum adapted for 80
 20 actuation by said dogs, a motor-spring, means interposed between said spring and dogs whereby the latter derive motion from the former, and a motor-shaft actuatable by 85
 25 said drum.
20. In combination, a cranking-sleeve, a cranking-pinion actuatable thereby, a cranking-spur actuatable by said pinion, a hub fixed to said spur, centrifugal dogs carried by 90
 30 said hub, a friction-drum actuatable by said dogs, a motor-shaft driven by said drum, and a spring for actuating said cranking-sleeve.
21. In combination, a cranking-sleeve, a cranking-pinion actuatable thereby, a cranking-spur actuatable by said pinion, a hub fixed to said spur, centrifugal dogs actuatable by 95
 40 said hub, a friction-drum actuatable by said dogs, a motor-shaft driven by said drum, a motor-spring, and means for locking a portion 100
 45 of said elements from rotation.
22. In combination, a spring-shaft, a torsion-spring coiled thereon, a cranking-sleeve, a cranking-pinion fixed on said sleeve, a ratchet-wheel having a clutch-face 105
 50 fixed on said shaft, a pawl for engaging said ratchet, a rewind-wheel rotatably mounted on said spring-shaft and provided with a clutch face adapted for engagement with the one recited, a rewind pinion in mesh 110
 55 therewith, a motor-shaft on which it is fixed, a friction drum fixed on said motor-shaft, centrifugal dogs adapted for co-action therewith and a cranking-spur rotatably mounted 115
 60 on said motor-shaft.
23. In an engine-starter, a motor-shaft, a spring-shaft parallel therewith, a spring coiled longitudinally of and on said spring-shaft, starter-mechanism interposed between 120
 65 said shafts, adapted to drive them in con- 125
 trary directions and actuatable by said spring and means for regulating the tension of the spring while it is not operating.
24. In an engine-starter, a pair of co-acting clutch-members normally in engagement, a motor-spring, a motor-shaft, an engine-shaft for driving it, means interposed between said motor-shaft and clutch-members whereby the latter are rotated to thereby store energy in said spring, means interposed between one of said clutch-members 75
 and said spring whereby the coiling thereof effects disengagement of said clutch-members, and means for holding them out of engagement at will.
25. In an engine-starter, a pair of co-acting 80
 15 clutch-members normally in engagement, a spring-shaft, a motor-spring coiled in the direction of its axis thereon, a motor-shaft, an engine-shaft for driving it and means interposed between said motor-shaft 85
 and clutch-members whereby the latter are rotated to thereby coil and store energy in said spring, the continued coiling of said spring contracting its diameter and extending its length, whereby one of said clutch-members is drawn from engagement with 90
 the other.
26. In an engine-starter, a pair of co-acting 95
 15 clutch-members normally in engagement, a spring-shaft, a motor-spring coiled in the direction of its axis thereon, a motor-shaft, an engine-shaft for driving it, means interposed between said motor-shaft and clutch-members whereby the latter are rotated to thereby coil and store energy in 100
 100 said spring, the continued coiling of said spring contracting its diameter and extending its length, whereby one of said clutch-members is drawn from engagement with the other, and means for preventing said 105
 spring from uncoiling.
27. In an engine-starter, a pair of co-acting 105
 15 clutch-members normally engaged, a spring-shaft, a motor-spring coiled in the direction of its axis thereon, a motor-shaft, 110
 an engine-shaft for driving it, means interposed between said motor-shaft and clutch-members whereby the latter are rotated to thereby coil and store energy in said spring, the continued coiling of said spring contracting its diameter and extending its length, whereby one of said clutch-members 115
 is drawn from engagement with the other, means for preventing said spring from uncoiling, and means for releasing the last recited means, whereby said spring is permitted to uncoil.
28. In an engine-starter, an elongated 120
 125 spring-shaft, a spring coiled thereon and adapted for contraction and expansion in the direction of its axis, starter elements for torsionally acting on said spring and thereby expanding it, a clutch-member

adapted to be drawn longitudinally by the expansive action of said spring, and means for imparting movement to said starter elements to cause them to act on said spring 5 as stated.

29. In an engine-starter, a pair of co-acting clutch-members in engagement, a motor-spring, a motor-shaft, an engine-shaft for driving it, means interposed between said 10 motor-shaft and clutch-members whereby the latter are actuated to thereby store energy in said spring, and means interposed between one of said clutch-members and said spring whereby the coiling and consequent elongation thereof effects disengagement of said clutch-members.

30. In an engine-starter, a casing, a cranking-sleeve rotatable in a bearing therein and projecting therefrom, a spring-shaft rotatable in said sleeve and projecting therefrom, a spring coiled on said shaft, one of its ends secured to said sleeve and the other to said shaft, means for holding said sleeve from rotation, a motor-shaft, and motor-shaft-actuated means for rotating said spring-shaft whereby energy is stored in said 20 spring.

31. In an engine-starter, a casing, a cranking-sleeve rotatable in a bearing therein, a spring-shaft rotatable in said sleeve and projecting therefrom, a spring coiled on said shaft, one of its ends secured to said shaft and the other to said sleeve, means for holding said sleeve from rotation, a motor-shaft, motor-shaft-actuated means for rotating said spring-shaft whereby energy is stored in said spring, means for locking the spring in energized position, and means for releasing it whereby the motor-shaft is 30 caused to rotate.

32. In an engine-starter, a motor-shaft, an elongated spring-shaft, coacting clutches one of which is connected to the spring-shaft, a spiral spring arranged longitudinally 45 thereof and directly thereon and adapted to draw one of said clutches out of engagement with the other, means for axially contracting or expanding the spring, starter elements adapted to store energy in said 50 spring, means for retaining said energy in said spring, and means for releasing the last recited element to operate said starter elements.

33. In combination in an engine-starter, a 55 spring-shaft, a spiral motor-spring coiled thereon, a cranking-sleeve rotatable by said spring, an engine-shaft, and centrifugally-operating dogs driven from said sleeve to rotate the engine-shaft.

60 34. In an engine-starter, a motor-shaft, a spring-shaft, coacting clutches one of which is connected to the spring-shaft, a spring having coils of substantially the same diameters, embracing the spring-shaft and se-

cured thereto at one end, said spring adapted to draw one of said clutches out of engagement with the other, means for axially contracting or expanding the spring while it is not in operation, means adapted to store energy in said spring, means for holding 70 said spring in energy-storing position, and means for releasing said spring in order that it may exert its energy.

35. In combination, a power-spring, a cranking-sleeve adapted in one operation to 75 be actuated by said spring and in another operation to hold one end of said spring stationary, a cranking-pinion actuated by said sleeve, a cranking-spur actuable by said pinion, a hub fixed to said spur, centrifugal dogs carried by said hub, a friction drum actuable by said dogs, and a motor-shaft driven by said drum.

36. In combination, a power-storing 85 spring, a cranking-sleeve for storing power therein, a cranking-pinion fixed on said sleeve, a cranking-spur actuable by said pinion, a hub fixed to said spur, centrifugal dogs carried by said hub, a friction drum actuable by said dogs, and a motor-shaft 90 driven by said drum.

37. In an engine-starter, co-acting clutch members, an elongated spring-shaft, a motor-spring coiled spirally thereon, a motor-shaft, an engine-shaft, and means interposed 95 between said clutch members and motor shaft whereby the former are rotated to thereby store power in said spring, the continued rotations of said clutch members 100 elongating said spring in the direction of its axis and thereby moving said spring-shaft longitudinally to withdraw one of said clutch members from engagement with the other.

38. In an engine-starter, co-acting clutch 105 members, a motor-spring coiled spirally thereon, a motor-shaft, an engine-shaft engaged therewith, means interposed between said clutch members and motor-shaft whereby the former are rotated to thereby store 110 power in said spring, the continued rotations of said clutch members elongating said spring in the direction of its axis and thereby moving said spring-shaft longitudinally 115 to withdraw one of said clutch members from engagement with the other, and means for preventing said spring from exhausting its energy until it is desired that it do so.

39. In an engine-starter, co-acting clutch members, a motor-spring coiled spirally 120 thereon, a motor-shaft, an engine-shaft engaged therewith, means interposed between said clutch members and motor shaft whereby the former are rotated to thereby store power in said spring, the continued rotations of said clutch members elongating said spring in the direction of its axis and thereby moving said spring-shaft longitudinally 125

to withdraw one of said clutch members from engagement with the other, means for preventing said spring from exhausting its stored energy until it is desired that it do so, 5 and means for releasing the last recited means.

40. In an engine-starter, a motor-spring, a shaft to which one of its ends may be secured, means adapted for selective engagements with said shaft for effecting such securing, an engine-shaft, a cranking-sleeve on the first recited shaft, the other end of the spring secured thereto, and means interposed between said sleeve and engine-shaft 15 whereby the cranking-sleeve causes the engine-shaft to be rotated.

41. In an engine-starter, a spring-shaft, a motor-spring coiled longitudinally thereof and thereon, means for regulating the 20 tension of said spring while it is not in operation, a cranking-sleeve to which one end of the spring is secured, a cranking-pinion driven by said sleeve, a cranking-spur driven by said pinion, and a motor-shaft driven 25 by said spur.

42. In combination, a motor-shaft, an engine-shaft for driving it, clutch-mechanism

driven from said motor-shaft, a spring-shaft actuated by said clutch-mechanism, a spring coiled longitudinally of and on said 20 shaft and adapted to be energized thereby, and centrifugally actuated means for imparting motion, in one operation of the device, to said motor-shaft.

43. In an engine-starter, a spring-shaft, a 35 spring coiled longitudinally thereof and thereon and one of its ends secured thereto, said spring adapted to elongate as it is coiled, means for rotating said shaft in one direction to wind said spring by coiling it 40 from that one of its ends which is secured to said shaft, co-acting clutch-members, one of them drawn out of engagement with the other as the spring is wound, and engine-starter elements operable by said clutch- 45 members when they are engaged.

In testimony that I claim the foregoing as my invention, I hereto subscribe my name at Galesburg, Knox county, Illinois, this 21st day of September, 1914.

EDWARD H. OVERHOLT.
